UNITED STATES PATENT OFFICE.

EGBERT ABADIE, OF PARIS, FRANCE.

MACHINE FOR PRINTING ENDLESS PAPER.

SPECIFICATION forming part of Letters Patent No. 276,547, dated May 1, 1883.

Application filed March 8, 1883. (No model.) Patented in Belgium January 3, 1883, and in France January 15, 1883.

To all whom it may concern:

Be it known that I, EGBERT ABADIE, a citizen of the Republic of France, residing at Paris, have invented a new Machine for Printing Endless Paper, (for which I have obtained Letters Patent in France, dated January 15, 1883, for fifteen years, and in Belgium, dated January 3, 1883, for fifteen years;) and I do hereby declare that the following is a full, clear, and exact description of the invention, which will enable others skilled in the art to which it appertains to make and use the same, reference being had to the accompanying drawings, and to the letters or figures of reference marked thereon, which form a part of this specification.

This invention consists in the new combination of parts and means for printing on long ribbons of paper. The cigarette-paper, cut into continuous bands of any length and width, rolled on bobbins of any size, and susceptible of receiving a trade-mark, an emblem, a title, &c., which is to be placed at variable or invariable, but always mathematically-exact, distances apart, is unrolled beneath an apparatus furnished with stamps or characters, and endowed with a movement which effects the stamping or impression of trade-marks, emblems, &c., at distances apart previously determined, and justified by the movement of the paper, which is operated regularly and at a regulated suitable speed. After passing the stamping apparatus the papers pass beneath an apparatus furnished with boxes containing bronze-powder, which is spread over the impressions in order to bronze them in any shade, and is fixed thereto smoothly and firmly by the passage of the printed and bronzed paper beneath a rubbing-roller covered with cloth, velvet, or skin.

The annexed drawings illustrate an arrangement of machinery for making the said impressions or stamps, and for bronzing the same on long bands of paper. Figure 1 is a side elevation, Fig. 2 is a vertical section, and Fig. 3 a plan view, of the machine.

The mechanism is mounted on two standards, *a*, on which it rests by two bearings, *b*, and two arms, *c*. This mechanism consists of two cast-iron side frames, *d*, connected together by cross-pieces *d'* *d''* *d'''* and by the shafts *f* *g* *h* *i* *j* of the movable parts. These side frames

rest in the bearings *b* by the cross-pieces or blocks *d'* and in the bearings in the ends of the arms *c* by two projections or blocks, *d''*. The shaft *f* carries the roller *f'* for drawing forward the paper. This roller is of gun-metal, 55 roughened by the file and rendered a little unctuous, (*ongueux*.) The shaft *g* carries the printing or stamping instrument, which is shown with three equidistant parts, *g'* *g''* *g'''*, shaped to receive either a stereotype or printing-type.

Directly over the shaft *g* is the shaft *h*, carrying the inking-roller *h'*, which is supplied with ink by a roller, *k*, arranged at the side and furnished with ink either by a hand-roller 65 or any other suitable inking-instrument. The roller *k* is mounted at the end of two eccentric-bars, *l l*, the eccentrics for which, *l'*, are keyed onto the shaft *f*. The bars *l* oscillate round joints *l''*, fixed to the standards *a*.

Following the printing apparatus is arranged the bronzing-box *p*, in which turns a pallet, *q*, fixed on the shaft *i*. Each revolution of this pallet causes the bronze-powder to fall through the slit or holes *p'* at the lower part of the box. 75 The shaft *j* carries the cylinder *j'*, which is covered with cloth, velvet, or skin. The shafts *f*, *h*, and *j* turn in bearings fitted into the side frames, *d*. These bearings may be moved by the screws *f''*, *h''*, and *j''*, so as to allow of the 80 most accurate adjustment of the parts *f'*, *h'*, and *j'*.

Below the printer *g'* *g''* *g'''* and the cylinder *j'* is placed a table, *t*, covered with cloth or other suitable material, *t'*. The position of this table can be regulated at pleasure by the screws *t''* *t'''*. The endless paper which it is required to stamp and bronze is rolled on the bobbins *A*, which are placed in the bearings of the brackets *x*, fixed to the standards *a*. From 90 these bobbins the paper is conducted over the roller *f'*, then under the printer or stamper *g'* *g''* *g'''*, the bronze-box *p*, and the cylinder *j*, and over the table *t*.

The shaft *f*, from which the machine takes 95 its motion, is operated by hand or by power. It transmits the motion by two equal spur-wheels, *m* *n*, to the shaft *g*, and by a pinion, *q*, to the shaft *i*. This pinion is one-third of the diameter of the spur-wheels *m* and *n*. The 100

shaft *f*, by means of the eccentrics *l'*, moves the inking-roller *k* to and fro in order to cause intermittent contacts between this roller *k* and the roller *h'*.

5 It will be understood that the regular movement of the roller *f'* delivers the endless paper *P* uniformly to the stamping, bronzing, and finishing instruments, and that the said paper is then rolled up onto other bobbins by any 10 suitable and known means.

As above described, the frames *d* are carried at *d'* and *d''* on the bearings *b* and *c*. They may be turned round the cross-piece *d'*, and thus access be obtained to the working parts 15 of the machine either for cleaning, repairing, or replacing.

The general arrangement and details may be varied as required without departing from the nature of the invention.

I claim—

20 The combination of the frame *a*, having bearings *b* and *c*, with the frame *d*, having supporting-blocks *d'* and *d''*, table *t*, rollers *f g h j*, lever *l*, eccentric *l'*, joint *l'*, box *p*, shaft *i*, and pallet *v*, all arranged for operation substantially as herein shown and described.

EGBERT ABADIE.
